(57) **CLAIM**

The ornamental design for a multimedia booth, as shown and described.

DESCRIPTION

This application is related to two co-filed applications for design patent, both entitled "Multimedia Booth," having U.S. Design patent application Ser. Nos. 29/468,681 and 29/468,699, invented by the same inventors and filed on even date herewith.

FIG. 1 is a perspective view of a multimedia booth showing my new design;

FIG. 2 is a perspective view thereof;

FIG. 3 is a right side view thereof;

FIG. 4 is a left side view thereof;

FIG. 5 is a front view thereof;

FIG. 6 is a back view thereof;

FIG. 7 is a top view thereof; and,

FIG. 8 is a bottom view thereof.

The broken lines illustrate portions of the multimedia booth that do not form a part of the claimed design.
